ATTORNEY.

UNITED STATES PATENT OFFICE.

WILLIS F. EPPERSON, OF LADOGA, INDIANA.

GLUING-MACHINE.

SPECIFICATION forming part of Letters Patent No. 707,219, dated August 19, 1902.

Application filed November 19, 1901. Serial No. 82,881. (No model.)

To all whom it may concern:

Be it known that I, WILLIS F. EPPERSON, a citizen of the United States, residing at La-
5 doga, in the county of Montgomery and State
of Indiana, have invented certain new and
useful Improvements in Gluing-Machines, of
which the following is a specification.

The object of my said invention is to pro-
vide a simple and inexpensive gluing-ma-
chine by means of which glue may be rapidly,
efficiently, and economically applied to the
sides or edges of pieces which are to be glued
together.

A machine embodying my said invention
15 will be first fully described, and the novel
features thereof then pointed out in claims.

Referring to the accompanying drawings,
which are made a part hereof, and on which
similar reference characters indicate similar
20 parts, Figure 1 is a top or plan view of a glu-
ing-machine embodying my said invention;
Fig. 2, a longitudinal vertical sectional view
of the same as seen when looking in the di-
rection indicated by the arrows from the dot-
25 ted line 2 2 in Fig. 1; Figs. 3 and 4, trans-
verse vertical sectional views as seen when
looking in the direction indicated by the ar-
rows from the dotted lines 3 3 and 4 4, re-
spectively, in Figs. 1 and 2; and Fig. 5, a de-
30 tail vertical sectional view through one of the
bearings of the gluing-wheel as seen from
the dotted line 5 5 in Fig. 1.

My improved gluing-machine consists of a
suitable receptacle for hot water, steam, or the
35 like by means of which the glue is kept in a
liquid condition to which steam or hot-water
pipes 10 and 11 are preferably connected and
which is composed of an outer shell 12 and a
top 13, the latter of which contains a chamber
40 14 for the glue. The two parts 12 and 13 are
secured together, preferably by screws 15, and
a gasket or packing-strip 16 is interposed for
the purpose of making a fluid-tight joint.

Resting on the top part 13 between suitable
45 lugs 17 are the journals of the glue-applying
wheel, which wheel is composed of the parts
18, 19, and 20. The two parts 18 and 19 are
alike, each being a disk with a groove in its
periphery, while the part 20 is preferably a
50 thin plate of sheet metal, slightly larger in di-
ameter than the parts 18 and 19, with its edge
which projects beyond said parts toothed or

serrated, and thus composed of or provided
with a large number of fine sharp points.
The three parts composing the wheel are se- 55
cured together in any suitable manner, as
by the machine-screws 21. This construction
of this gluing-wheel I have found by practical
use to be of very great importance. When
the edge of a piece of lumber (or other part 60
to be glued) is run over the edge of this gluing-
wheel the fine teeth or points formed on the
periphery of the part 20 enter said part suffi-
ciently to prevent slipping and insure that the
two surfaces—that of the wheel and that of the 65
part being glued—shall move in unison, which
insures the even application of the glue over
the surface of the part being glued. The re-
maining portion of the surface of the gluing-
wheel is smooth and true except that small 70
peripheral grooves are formed therein, which
as the lower edge of the wheel revolves in
the body of liquid glue become filled there-
with, thus bringing up a greater quantity of
the glue than a perfectly-smooth-surfaced 75
wheel would and insuring a sufficient supply
to thoroughly unite the edges of the parts
over which it is spread by means of this ma-
chine. An adjustable scraper 22 is provided
80 by means of which any excess of glue is
scraped off and forced back into the recep-
tacle. This is shown as secured to the top
13 by means of a screw 23, which passes
through a slot in the scraper and engages
85 with a threaded hole in said top. Suitable
shields 24 and 25 are secured to the top 13
near the ends of the gudgeons to the wheel
and serve to keep the same from being acci-
dently thrown out of their bearings and
also protect them from dirt. 90

At a suitable point above and to one side
of the gluing-wheel I provide a guide 30,
which is carried on standards 31. The up-
per ends of these standards (to which the
guide is immediately secured) are slotted, and 95
the guide is thus adjustable in relation to the
wheel, accommodating the use thereof to
parts having greater or less thickness or
width, the adjustment being effected by suit-
able manipulation of the bolts 32. 100

Having thus fully described my said inven-
tion, what I claim as new, and desire to secure
by Letters Patent, is—

1. The combination, in a gluing-machine,

of a suitable receptacle for the glue, and a gluing-wheel mounted to revolve in said receptacle and composed of disks, one of which is of slightly-greater diameter than the others 5 and has a serrated edge, the points or teeth whereof are adapted to engage with the article being glued as the same passes over the wheel, whereby the surfaces are caused to move in unison, the periphery of said wheel 10 being otherwise free of parts extending above its bearing-face, all substantially as set forth.

2. The combination, in a gluing-machine, of a suitable receptacle for the glue, and a gluing-wheel mounted to revolve in said receptacle and composed of three disks, the two 15 side disks having circumferential grooves in their periphery but being otherwise smooth,

and the central disk being of somewhat greater diameter than the side disks and having a serrated edge the points or teeth whereof are 20 adapted to engage with the article being glued as the same passes over the wheel, whereby the surfaces are caused to move in unison, while a suitable supply of glue is distributed over said article on both sides of the point 25 where thus engaged.

In witness whereof I have hereunto set my hand and seal at Indianapolis, Indiana, this 16th day of November, A. D. 1901.

WILLIS F. EPPERSON. [L. S.]
